UNITED STATES PATENT OFFICE.

JOHN McCLURE AND ALEXANDER BINGS, OF PHILADELPHIA,
PENNSYLVANIA.

GAME APPARATUS.

SPECIFICATION forming part of Letters Patent No. 600,738, dated March 15, 1898.

Application filed April 29, 1897. Serial No. 634,325. (No model.)

To all whom it may concern.

Be it known that we, JOHN McCLURE and ALEXANDER BINGS, citizens of the United States, residing at Philadelphia, in the county 5 of Philadelphia and State of Pennsylvania, have invented a certain Improvement in Game Apparatus, of which the following is a specification.

Our invention relates to a new and amusing 10 game, the object of which is to imitate the playing of foot-ball; and it consists of a rectangular tray having the proper divisions marked thereon and the goals and touch-down cages located at each end of the tray, and the 15 playing is carried on by two persons, each having a "putter" adapted to take a sufficient hold upon the ball to transfer the latter from one portion of the tray to the other.

The accompanying drawing, which forms a 20 part of this specification, represents in perspective a game made in accordance with our improvement, showing the ball at the starting-point and one of the putters in the act of taking hold of said ball.

25 In the drawing, A represents the tray, which is here shown as oblong, having sides of sufficient height to retain the ball therein under ordinary circumstances, and at each end of the tray is placed a strip B, preferably of wood, so formed as to produce a goal C and the touch-down cages D. Upon the surface 30 of the tray are marked lines crosswise thereof which are designated by the numbers 10, 25, and 50, respectively, starting from each goal 35 and progressing inwardly, or any number of these lines may be used. In the center of the tray is inscribed a circle E, which is preferably of a suitable color, and upon this spot the ball F or other object is placed prior to the 40 starting of the game.

There are provided two putters, each consisting of a wire or rod G, having formed upon one end thereof a circular loop or ring H, and the outer end of the wire is provided with a 45 handle I for the manipulation of the device.

The method of playing the game consists in

placing the ball upon the central spot and each player holding his putter at his goal, and when the signal to start is given an effort is made by each player to grasp the ball with the 50 ring of the putter and force it into the goal of his opponent without removing the ball from the surface of the tray, and as this will be found difficult when both players have the same object in view and are attempting to 55 accomplish said object it will be seen that an exceedingly amusing and exciting game will be provided.

Many of the rules of an ordinary foot-ball game may be followed in the playing of this 60 game, and by so doing popular interest will be added to the inherent amusement and excitement of the game.

A game made in accordance with our improvement is inexpensive and may be played 65 in any locality upon a table, and affords much sport for both young and old.

Having thus fully described our invention, what we claim is—

In a game apparatus, an oblong tray having 70 sides to retain a ball therein, a flat strip placed at each end of the tray, said strips having deep indentations formed in the center of their edges and shallower indentations to each side thereof, the surface of the tray having 75 a circle marked thereon and lines running across, the circle being at the center of the tray and the lines at each end, a ball adapted to be moved from one portion to the other of the tray, said ball being of a size to fit snugly 80 in the center indentations, in combination with "putters" each having a ring at one end of a size to take hold of the ball to move it, substantially as described.

In testimony whereof we have hereunto affixed our signatures in the presence of two subscribing witnesses.

JOHN McCLURE.
ALEXANDER BINGS.
